UNITED STATES PATENT OFFICE.

HENRY J. FREY, OF PALMYRA, MISSOURI.

FILTER.

1,329,462.

Specification of Letters Patent. Patented Feb. 3, 1920.

Application filed July 30, 1918. Serial No. 247,373.

To all whom it may concern:

Be it known that I, HENRY J. FREY, a citizen of the United States, residing at Palmyra, in the county of Marion and State 5 of Missouri, have invented new and useful Improvements in Filters, of which the following is a specification.

This invention relates to filters, the main object of the invention being to produce a 10 filter for the purpose of filtering rain water on its passage or fall from the roof of a building or other structure to a cistern or reservoir by causing the water to pass through a body of filtering material such as 15 gravel, sand, or the like, of any degree of coarseness. The filter is so constructed that the water must pass not only in a downward direction but also in an upward direction through the filtering material, so that the 20 force of gravity will assist in purifying the water by retaining at the bottom of the filter body or casing, any kind of filth heavier than water, instead of helping to carry the same along through the filter, as 25 is the case when the water moves in a downward direction only. Any kind of filtering material, particularly sand, no matter how fine, may be used, by reason of the particular construction of the improved filter, 30 without too greatly retarding the flow of water and without liability of the sand or finer particles being carried into the cistern or reservoir, as in the case of the filter employing a bottom screen or strainer.

35 With the above and other objects in view, the invention consists in the construction, combination and arrangement of parts, as herein described, illustrated and claimed.

In the accompanying drawings; 40 Figure 1 is a vertical diametrical section through the improved filter.

Fig. 2 is a horizontal section through the same.

In the preferred embodiment of the invention, I employ a casing or filter body 1 of hollow cylindrical formation and of any suitable height and diameter, said casing being preferably formed of sheet metal and comprising a cylindrical side wall 2, a bottom wall 3 and a top wall 4, which may be provided with an annular depending cap or flange 5, so that it may be detachably fitted upon the top of the main body of the casing or form a displaceable top wall to 55 give access to the interior of the casing.

Extending through the top wall of the casing is the upper section of a downspout 6 which in the case of a house or dwelling will extend from the roof guttering downwardly to the filter. The downspout section extends well downwardly into the casing 1 and before reaching the bottom wall 3 of the casing, the lower end of the downspout section 6 is flared and considerably enlarged to form a frusto-conical discharge 65 end portion 7. The bottom edge 8 of said frusto-conical portion of the downspout section 6 is located and supported a considerable distance above the floor or bottom edge of the casing by legs or upright bracket 70 pieces 8' and the space below said bottom edge is closed by means of an annular strainer 9 preferably formed of meshed wire fabric of any suitable gage. The strainer is detachably placed about and held 75 in position by the legs and may be readily removed for the purpose of cleaning out the filter.

Arranged at one side of the center of the casing 1 and preferably adjacent to the 80 peripheral wall of said casing is a lower downspout section 10 which terminates at its upper end above the filtering material, the level of which is indicated at 12. The downspout section 10 extends through the 85 bottom of the casing and projects below the same as shown at 13, it being intended to lead said downspout section 10 to the cistern or reservoir to receive the filter water. In order to allow all water to drain from 90 the filter casing after a rain, the downspout section 10 is formed adjacent to the floor or bottom 3 with one or more small perforations or water drain ports 14, the same being of small size to prevent the filtering material from passing to the cistern or reservoir. 95

By reason of the frusto-conical shape of the discharge end portion 7 of the downspout section 6 within the casing 1, as shown and described, an outlet of increased area is 100 provided for the free flow of the water into the chamber 2 without gorging or choking the outlet or causing regurgitation or the discharge of the water unevenly or in jets or streams of a force liable to displace and compact or otherwise disturb the density or uniformity of distribution of the mass of filtering material. Thus objections of this character inherent in the use of a downspout having a restricted outlet or one of 110

uniform diameter therewith are avoided. Also by this construction coarse filtering material may be used in the chamber 2 below the level of the upper end of the outlet 5 7 for the rapid distribution of the water throughout the base of the chamber 2, while, owing to the smaller diameter of the downspout section 6, greater space is afforded above the level of the portion 7 to receive a 10 large amount of fine screen material in the upper portion of the chamber 2, this being desirable to secure efficiency and rapidity in the filtering action, owing to the fact that as the fine material filters more slowly than 15 the coarse a greater area of surface for the fine material is required in order to make the filter work fast enough. The portion 7 is also advantageous in that it acts as an overhead shield for the screen 9, preventing 20 the filtering material from packing down and around the screen and interfering with its proper operation. The construction further provides for the convenient use of a removable screen, as previously described.

25 I claim:

1. In a filter, the combination of a casing adapted to contain filtering material, an upper downspout section extending through the top of said casing, said downspout section having an enlarged frusto-conical lower end portion located in superposed and spaced relation to the floor of said casing, an annular strainer of greater diameter than the main body of said downspout extending 30 35 from the peripheral edge of the frusto-conical end portion of said downspout section to the floor of the casing, a lower downspout section extending through the bottom of the casing and terminating at its upper end below the top of said casing, and a body of filtering material supported by the floor of 40 45 the casing and extending around and above the frusto-conical portion of the upper

downspout section, and also around said strainer. 45

2. In a filter, the combination of a casing adapted to contain filtering material, an upper downspout section extending through the top of said casing and having an enlarged frusto-conical lower end portion located in superposed and spaced relation to the floor of said casing, an annular strainer of greater diameter than the main body of said downspout extending from the lower extremity of said downspout section to the 50 55 floor of the casing, a lower downspout section extending through the bottom of the casing and terminating at its upper end below the top of said casing, a body of filtering material supported by the floor of the 60 casing and extending around and above the frusto-conical portion of the upper downspout section, and also around said strainer, and supporting legs on the upper downspout section for supporting the bottom end 65 thereof in spaced relation to the floor of the casing, said strainer being detachably placed about and held in position by the legs.

3. In a filter, the combination of a casing adapted to contain filtering material, an upper downspout section extending through the top of said casing, said downspout section having an expanded frusto-conical lower end terminating above the bottom of the casing, a strainer inclosing the space between the bottom of the casing and lower peripheral edge of said frusto-conical lower end of the upper downspout section, an outlet for the discharge of the filtered water from the casing above the level of the filtering material, said strainer and frusto-conical expanded end of the upper downspout being arranged in the filtering chamber and surrounded by the filtering material. 75 80 85

In testimony whereof I affix my signature. 85
HENRY J. FREY.
